United States Patent Office

Des. 182,823

Patented May 20, 1958

182,823

BOAT HANDLE OR SIMILAR ARTICLE

Elizabeth S. Kent, Waterbury, Conn., assignor to Scovill Manufacturing Company, Waterbury, Conn., a corporation of Connecticut

Application June 17, 1957, Serial No. 46,608

Term of patent 3½ years

(Cl. D71—1)

Fig. 1

Fig. 2

Fig. 3

Fig. 4

Fig. 5

Fig. 1 is a perspective view of a boat handle or similar article showing my new design;

Fig. 2 is a side elevational view thereof;

Fig. 3 is a plan view thereof;

Fig. 4 is an elevational view looking at the left of Fig. 3; and

Fig. 5 is an elevational view looking at the right of Fig. 3.

I claim:

The ornamental design for a boat handle or similar article, substantially as shown.
